UNITED STATES PATENT OFFICE.

NORMAN W. CUMMINS, OF BRIDGEPORT, CONNECTICUT, ASSIGNOR TO THE BURNS & BASSICK COMPANY, OF BRIDGEPORT, CONNECTICUT, A CORPORATION OF CONNECTICUT.

GREASE-CUP.

1,148,289.

Specification of Letters Patent. Patented July 27, 1915.

Application filed March 26, 1913. Serial No. 756,983.

To all whom it may concern:

Be it known that I, NORMAN W. CUMMINS, a citizen of the United States, residing in the city of Bridgeport, county of 5 Fairfield, State of Connecticut, have invented certain new and useful Improvements in Grease-Cups; and I do declare the following to be a full, clear, and exact description of the invention, such as will enable others 10 skilled in the art to which it appertains to make and use the same.

This invention relates to certain new and useful improvements in grease cups and pertains more particularly to the means for 15 forcing the grease through the feed opening.

The primary object of the invention is to provide novel and improved means for feeding the lubricant, and to further provide 20 novel means for preventing retrograde rotation of the feeding element.

In the drawings: Figure 1 is a vertical sectional view of the invention; Fig. 2 is a side elevation; Fig. 3 is a section on the line 3—3 of Fig. 2; Fig. 4 is a section on the 25 line 4—4 of Fig. 2; Fig. 5 is a section on the line 5—5 of Fig. 2; and Fig. 6 is a fragmentary perspective view showing one of the ratchet teeth of the spring-held sliding collar.

30 The body 1 is formed with a reduced exteriorly threaded lower end 2 that is provided with an outlet opening 3, a collar or abutment 4 being suitably secured at the upper portion of the reduced end 2. The 35 upper end of the body is formed with an outwardly extending flange 4 that engages with a flange 5 which extends inwardly from a reinforcing member 6, the free upper end portion of the member being forced inwardly to engage on top of the flange 4 whereby the latter is clamped between the flange 5 and the flange 7 that is formed by forcing said upper end portion of the member 6 inwardly. The periphery of the reinforcing member 6 is exteriorly threaded and is engaged with a cap 8 that has a hexagonal head 9 to allow same to be manually rotated. The lower end of the cap 8 is offset or expanded at 10 so as to extend outwardly from the major portion of the cap, and the lower edge of said offset portion 10 is formed with cut-out portions 11 to provide ratchet teeth, which are preferably two in number. A knurled collar 12 is formed 45 with a hexagonal opening 13 at its center in

order to allow the collar to have sliding movements lengthwise of the body 1, but to prevent rotary movement thereof relative to the body.

A feature of the present invention consists in striking or pressing out ratchet teeth 14 from the body portion of the collar, which teeth are inclined with respect to the plane of the body of the collar in order to allow the ratchet teeth of the cap 8 to ride easily thereover. The ratchet teeth 14 which are struck out from the body of the collar 12 are closed on both sides, their front ends and the tops thereof, which results in maximum strength being imparted to the teeth, and increased wearing ability. A somewhat conical spring 15 has its lower end seating on the flange 4 and its upper end bearing against the body of collar 12, and being also engaged by the inner face of the knurled 50 portion of said collar.

By expanding or offsetting the lower end or the bottom portion of the cap, as above described, the cap is materially strengthened, and by forming the ratchet teeth on this expanded portion, the threads on the interior of the cap, are not interfered with or mutilated, in movement of the collar to the position where it abuts flange 5, or in movement of the cap to disengage same from the body, due to the fact that the ratchet teeth are located in a plane outside of or spaced from the plane in which the threads of the cap are located.

The body 1 is reduced above the abutment 4' at *a* to form a shoulder *b*, whereby, when it is desired to refill the body 1 with grease, collar 12 is forced downwardly against the action of the spring 15, to bring the opening of the collar 12 opposite to the reduced part *a* of the body 1, whereupon the collar is slightly turned to engage beneath the shoulder *b* to thus lock the collar against the action of the spring. The collar may be then rotated backwardly and removed. It will be apparent that the formation of the ratchet teeth is such that clockwise movement only of the cup 8 is permitted.

What is claimed is:

In a grease cup, a body of angular cross-section having a threaded upper end, and an abutment adjacent its lower end, a shoulder on the body and spaced above the abutment, a collar extending in a plane at right angles to the longitudinal axis of the body 105 110

having an angular opening which slidably receives the body, a cap threaded over said threaded end of the body, the extreme lower edge of the cap having teeth formed therein, 5 and the lower end of the cap being vertically outwardly offset, and teeth on the upper face of the collar which engage the teeth of the cap and permit of rotation of the latter in one direction, a coil spring between 10 the abutment and collar, and a depending flange on the collar extending beyond the offset end of the cap to provide an exposed

hand gripping part which enables the collar to be depressed and partially rotated to engage under the shoulder whereby to hold 15 the collar inoperative during removal of the cap and filling of the cup.

In testimony whereof I affix my signature in presence of two witnesses.

NORMAN W. CUMMINS.
